(57) **CLAIM**

The ornamental design for the hair trimmer, as shown and described.

DESCRIPTION

FIG. 1 is a top perspective view of the present hair trimmer; FIG. 2 is a left side view of same;

FIG. 3 is a right side view of the hair trimmer of FIG. 1

FIG. 4 is a front view of same;

FIG. 5 is a rear view of the hair trimmer of FIG. 1;

FIG. 6 is a top view of same; and,

FIG. 7 is a bottom view of same.

The structure shown in broken lines illustrates portions of the hair trimmer that forms no part of the claimed invention.
